UNITED STATES PATENT OFFICE.

ALLEN A. VAN ORSDALE, OF PHILADELPHIA, PENNSYLVANIA, ASSIGNOR TO CELESTIN SANER, OF PHILADELPHIA, PENNSYLVANIA.

LUBRICATOR.

1,401,836.

Specification of Letters Patent. Patented Dec. 27, 1921.

Application filed December 18, 1920. Serial No. 431,631.

To all whom it may concern:

Be it known that I, ALLEN A. VAN ORSDALE, a citizen of the United States, residing at Philadelphia, in the county of Philadelphia and State of Pennsylvania, have invented new and useful Improvements in Lubricators, of which the following is a specification.

This invention relates to lubricators and it has more particular reference to that type or form of lubricator which is dependent upon the vibrations of the machine or engine to which it is applied for feeding the lubricant to the desired part or parts; in other words, my invention has reference more specifically to lubricators the feed whereof is incident to the surrounding vibratory conditions whereby an automatic feed consonant with the degree of vibration results.

The main object of my present invention is to provide a lubricator of the nature referred to which is more applicable for industrial purposes, that is to say which is usable wherever it is essential that moving parts should be kept evenly lubricated.

Another object of this invention is to provide a vibratory feed lubricator the feed whereof can be regulated to meet different conditions, said regulation being effected by means external to the lubricator.

A further object resultant to my present invention is the provision of means whereby the vibratory feed lubricator can be quickly replenished with lubricant without the disconnection of any of the parts.

A still further object of my invention is the provision of a vibratory feed lubricator characterized by means for trapping any foreign matter which may accidentally become associated in the lubricant whereby the feed is rendered absolutely smooth and free from any tendency to clogging or flooding.

With the foregoing and other objects in view as will become more apparent as the description proceeds my present invention consists essentially in the novel features of construction, combination and arrangements of parts hereinafter fully described and more specifically defined by the appended claims.

In the further disclosure of the invention reference is to be had to the accompanying sheet of explanatory drawings, constituting a part of this specification, and in

which like characters of reference designate the same or similar parts in all the views.

Figure 1 is a central vertical section through a sight-feed lubricator embodying my present improvements and showing the valve in open or lubricant feeding position.

Fig. 2 is a similar central vertical section but showing the valve closed and the lubricator refilling mechanism open.

Fig. 3 is an outside elevation of the structure shown by Figs. 1 and 2.

Fig. 4 is a top plan view; and,

Fig. 5 is a transverse section on the line 5—5 in Fig. 3.

Referring more particularly to the views the numeral 10 designates the base or lower part of my improved lubricator which is preferably of dished formation in cross section, and it is provided at its upper part 75 with a vertically directed rim 11 and a circumscribing flange 12 for the purposes later on to be explained. Formed integral with the said lower part 10 is an axial extension or cylindrical portion 13 terminating in an externally threaded nipple 14 by means of which the lubricator can be connected in position or removed when desired. Formed at diametrically opposed points in the cylindrical portion 13 are sight openings 15 and fitting snugly in said cylindrical portion is a short length of glass tube 16 which seats at its lower and upper ends between washers 17 of appropriate material, and in order to provide an effective means 85 for locking the glass tube 16 in place I formed at diametrically opposed points in the cylindrical portion 13 are sight openings 15 and fitting snugly in said cylindrical portion is a short length of glass tube 16 which seats at its lower and upper ends between washers 17 of appropriate material, and in order to provide an effective means 90 for locking the glass tube 16 in place I

preferably employ a funnel-shaped nipple 18 which is screw-threaded at 19 into the base or lower part whereby a liquid-proof joint is insured as and between the glass tube 16 and the cylindrical portion 13. It is also to be especially noted that a fundamental feature incident to the employment of the funnel-shaped nipple 18 is that it is centrally apertured at 20 so that the lubricant is fed axially central to the discharge orifice or passage 21 in the threaded nipple 14 while at the same time the said lubricant cannot percolate around and becloud the glass registering with the sight openings 15. This latter feature I deem of very great importance as it makes provision for the accurate adjustment of the feed at all times, but I wish it clearly and emphatically understood that it is in no sense 105 110

to be construed as obligatory to provide this sight-feed feature of my invention, and it is only here described as being a part of the particular embodiment shown in the drawings.

Formed integral with and internally of the base or lower part 10 are radially projecting lugs or projections 22 which are notched out at 23 to seat a concavo-convex 10 or dished diaphragm 24 which when in place provides a series of openings between the peripheral edge thereof and the inner wall of the part 10 intervening the said lugs or projections for the purpose later on set 15 forth; and it is also to be noted that this concavo-convex or dished diaphragm 24 is mounted in spaced relation relative to the inner lower surface or wall of the base part 10.

20 Frictionally or otherwise seated in the upper portion of the base 10 and within the aforesaid vertically directed rim 11 is a diaphragm 25 which is provided with an axially central depending and internally 25 threaded flange 26, said diaphragm 25 also constituting the base or bottom for an appropriate cylindric reservoir member 27 which seats on a washer 28, and it is to be remarked that while I have shown this reservoir member 27 as made of glass, it will 30 be apparent that it may be made of any other translucent material, or it may be formed integrally with the diaphragm 25 and therefore not of a transparent nature.

35 The cover proper 29 is preferably formed with a depending lip 30 which seats snugly upon the upper end of the reservoir 27, a washer 31 being interposed to insure an air and dust-proof joint and in order to clamp 40 the parts 10, 27, and 29, firmly together, I employ a plurality of bolts 32 which are passed through holes in the flange 33 of the cover 29 and threaded into the aforesaid 45 circumscribing flange 12 of the base 10, lock-nuts 34 being then applied and thereby insuring an absolutely dust and moisture-proof structure.

Centrally of the cover 29 is a depending 50 boss or flanged part 35 which is bored at 36 for the passage of a tube 37 having apertures or holes 38 therein, and said tube 37, it will be noted is formed at its upper end with a flange 39, and at its lower part it is externally threaded at 40 for engagement in 55 the above referred to internally threaded flange 26. Shrouded or shrunk firmly onto the flange 39 is an extension 41 in the nature of a knurled or serrated head-piece or manipulating member 42 provided on its upper face with graduations 43 readable to the right or left hand from a zero point 44 on the cover 29 and it will be seen on an examination more particularly of Fig. 4 that "fast" and "slow" markings are also depicted on said cover for the purpose later

on explained. Adjustably threaded into the lower end of the tube 37 is a valve seat member 45 formed to coöperate with an upwardly seating valve 46 integral with or adjustably mounted on the lower end of a 70 valve stem or rod 47, the upper end whereof is screw threaded into a cap 48 provided with an annular depending flange 49 arranged to fit snugly over the upstanding flange or extension 41 on the aforementioned 75 head-piece or manipulating member 42. This cap 48 is also formed with an inner concentric depending tubular part 50 having an aperture 51 in one side thereof and it is to be noted that this latter part 50 is made a friction fit for the extension 41 and upper end of the tube 37 when the parts are in closed position as shown in Fig. 1. It is also to be particularly noted that the tubular part 50 is limited in its outward 80 movement by the valve 46 seating upwardly against the valve seat member 45 as shown in Fig. 2, whereupon the aperture 52 is brought into exposed position above the extension 41 when lubricant can be injected 85 therethrough to replenish the reservoir 27 when empty as hereafter explained.

The assembly and operation of my improved lubricator are briefly as follows:— The glass tube 16 is fitted into the cylindric portion 13 of the base 10 and firmly seated liquid and dust-proof by the funnel-shaped nipple 18, whereupon the concavo-convex diaphragm 24 is sprung into connection with the notched out parts 23 100 of the radial lugs or projections 22. The diaphragm 25 is next seated and the reservoir member 27 and cap 29 assembled as shown, whereupon the bolts 32 are fitted to clamp said parts to the base or lower part 10 and the lock-nuts 34 applied whereby liquid-proof joints are insured. The valve 46 and cap 48 are next adjusted relative to the valve seat 45 within the tube 37 so that a 105 slideable limit is insured for the purpose of bringing the aperture 51 just clear of the extension 41 as hereinbefore explained, whereupon the tube 37 is passed into the reservoir 27 through the bore 36 in the cover 29 and threaded downward through 110 the depending flange 26 of the diaphragm 25 to the requisite extent to create a liquid seal 52—Fig. 1. When the parts are assembled as shown lubricant 53 is injected into the reservoir 27 through the aperture 51 after the valve 46 and its attached cap 48 have been withdrawn by an upward pull on the knob 54 as shown in Fig. 2, said lubricant being filled in to approximately the level shown, and it is to be here noted that 115 when the cap 48 is withdrawn the valve 46 closes upwardly upon its seat 45 and prevents any downward flow of the lubricant, whereas free access of said lubricant 53 into the reservoir 27 takes place through the 120

holes or perforations 38 in the tube 37. A downward pressure on the knob 54 or cap 48 will move the valve 46 away from its seat 45 thereby allowing the lubricant to gradually discharge downwardly through said seat 45 and lower end of the tube 37 into the concavo-convex or dished diaphragm 24 until it rises to the aforementioned liquid sealing level 52, that is to say when it rises 10 to a level in register with the bottom of said tube 37 as shown in Fig. 1. Now assuming that the lubricator is installed on a machine or engine subject to constant or intermittent vibration it will be readily seen that 15 any vibration set up will cause the lubricant 53 contained in the diaphragm 24 to be washed to one side or the other over the edge of said diaphragm, whereupon it will flow downwardly in the base 10 to the funnel-shaped nipple 18 and be directed axially central to the orifice 20 therein from whence it will drop globule by globule or flow axially central to the passage or discharge orifice 21 and be conducted to the 20 part or parts to be lubricated. Now it will be obvious that each "splash" over of the lubricant from the concavo-convex or dished diaphragm 24 will temporarily break the liquid seal 52 at the bottom of the tube 37 25 and thereby cause an automatic downward feed of said lubricant 53 to create a fresh liquid seal, and further that the feed of the lubricant 53 will be correspondingly increased or decreased consonant with the frequency of the vibrations, an air vent 55 being provided above the upper level of the edge of the diaphragm 24 for the prompt replacement of the air which bubbles up through or past the lower end of the tube 37 after each "splash" and thereby aiding very materially in the prompt resealing after each said splash.

From the foregoing description it will be readily seen that the action just described 45 will be set up synchronously with and as frequent as the vibrations take place, and that the feed of lubricant will continue in more or less regulated quantity to the part or parts to be kept lubricated, while it will 50 be clearly apparent that the quantity of lubricant feed can be regulated at any time by simply turning the manipulating member 42 one or more graduations to the right or left-hand relative to the zero mark 44 55 accordingly as it is desired to increase or diminish said feed, it being of course clearly comprehended that the sight openings 15 are provided for inspection purposes in this connection. Still further it will be observed 60 that should any solid or like foreign matter be contained in the lubricant it will collect in the bottom of the reservoir 27 below the level of the lowermost holes 38 in the tube 37 and can be removed when requisite or 65 necessary, also that in the event of any

trouble with a lubricator constructed and arranged as above described and shown the various parts can be readily separated, and vice versa just as promptly reassembled.

Finally it will be readily recognized that 70 a lubricator constructed and adapted for operation as set forth will possess numerous other advantages incident to its novel formation, and that it may be employed in any situation where there is sufficient vibration 75 to create a "splash" of the lubricant over the upper peripheral edge of the concavo-convex dished diaphragm 24, and while I have described and illustrated one practical embodiment of my invention it is to be 80 clearly understood that I do not limit myself to the precise details of construction, combination and arrangement of parts disclosed, as various changes in the shape, arrangement and manner of manipulating 85 them can be easily evolved without departing from the spirit and scope thereof, and it is intended hereby to include all such reasonable modifications as may fairly be construed as falling within the scope and ambit 90 of the appended claims.

Having described my invention, what I claim as new and desire to secure by Letters Patent, is:—

1. A vibratory feed lubricator comprising 95 a basal portion having an outlet therefrom, a funnel shaped nipple seated over said outlet, a dished diaphragm mounted in spaced relation within said basal portion, a lubricant reservoir mounted on and adapted for clamping engagement to said basal portion, 100 a perforate tube axially longitudinal of the reservoir and having threaded connection in the lower end thereof, means for manipulating said perforate tube whereby its lower 105 end may be regulated relative to the dished diaphragm, and valve including telescopic means movable longitudinally of the aforesaid perforate tube whereby the lubricator 110 may be filled when necessary.

2. A vibratory feed lubricator comprising a basal portion having an outlet therefrom, a funnel shaped nipple seated over said outlet, a dished diaphragm mounted in spaced relation within said basal portion, a lubricant reservoir including a cylindric body portion, a base having an internally threaded extension and a centrally apertured cover, means for clamping said body, base and cover firmly together, a perforate tube for 115 passage longitudinally through the apertured cover and engagement in the aforesaid threaded extension, means for manipulating said perforate tube whereby its lower 120 end may be regulated relative to the dished diaphragm, a valve seat in said perforate tube, and an upwardly seating valve and associated telescopic member movable longitudinally within the perforate tube whereby 125 the lubricator may be filled when necessary. 130

3. A vibratory feed lubricator comprising a basal portion having an outlet therefrom, a funnel shaped nipple seated over said outlet, a dished diaphragm mounted in spaced relation within said basal portion, a lubricant reservoir including a cylindric body portion, a base having an internally threaded extension and a centrally apertured cover, means for clamping said body, base and cover firmly together, a perforate tube for passage longitudinally through the apertured cover and engagement 70 in the aforesaid threaded extension, an extension on the upper end of said perforate tube having a graduated flange for manipulation relative to a zero mark on the reservoir cover whereby the lower end of said perforate tube may be regulated relative to the dished diaphragm, an adjustable valve seat threaded 75 into the perforate tube, and an upwardly seating valve and associated telescopic member movable longitudinally within the perforate tube whereby the lubricator may be filled when necessary.
- 25 4. A vibratory feed lubricator comprising a basal portion having an outlet therefrom, a funnel shaped nipple seated over said outlet, a dished diaphragm mounted in spaced relation within said basal portion, a lubricant reservoir including a cylindric body portion, a base having an internally threaded extension and a centrally apertured cover, means for clamping said body, base and cover, firmly together, a perforate tube for passage 80 longitudinally through the apertured cover and engagement in the aforesaid threaded extension, an extension on the upper end of said perforate tube having a graduated flange for manipulation relative to a zero mark on the reservoir cover whereby the lower end of said perforate tube may be regulated relative to the dished diaphragm, an adjustable valve seat threaded 85 into the perforate tube, and an upwardly seating valve and associated telescopic member movable longitudinally within the perforate tube whereby the lubricator may be filled when necessary.
- 30 5. A vibratory feed lubricator comprising a basal portion having an outlet therefrom, a funnel shaped nipple seated over said outlet, a dished diaphragm mounted in spaced relation within the basal portion, and a lubricant reservoir mounted on and adapted for clamping engagement thereto, the combination of a perforate tube for passage 90 longitudinally through the reservoir and threaded engagement in the base thereof, an extension on the upper end of said perforate tube having a graduated flange for manipulation relative to a zero mark on the aforesaid reservoir whereby the lower end of said perforate tube may be regulated relative to the dished diaphragm, and means movable 95 relative to and longitudinally of the perforate tube whereby the lubricator may be filled when necessary.
- 35 6. In a vibratory feed lubricator comprising a basal portion having an outlet therefrom, a funnel shaped nipple seated over said outlet, a dished diaphragm mounted in spaced relation within the basal portion, and a lubricant reservoir mounted on and adapted for clamping engagement thereto, the combination of a perforate tube for passage 100 longitudinally through the reservoir and threaded engagement in the base thereof, an extension on the upper end of said perforate tube having a graduated flange for manipulation relative to a zero mark on the aforesaid reservoir whereby the lower end of said perforate tube may be regulated relative to the dished diaphragm, and means movable 105 relative to and longitudinally of the perforate tube whereby the lubricator may be filled when necessary.
- 40 7. In a vibratory feed lubricator comprising a basal portion having an outlet therefrom, a funnel shaped nipple seated over said outlet, a dished diaphragm mounted in spaced relation within said basal portion, a lubricant reservoir mounted on and adapted 110 for clamping engagement thereto, a perforate tube axially longitudinal of the reservoir and having threaded connection in its lower end and means for manipulating said perforate tube whereby its lower end may 115 be moved toward or away from the dished diaphragm, the combination of a cap for seating on the reservoir said cap having an inner concentric apertured tubular part for telescopic engagement in the upper end of the aforesaid perforate tube, and a valve 120 stem axially depending from said cap, provided with an upwardly seating valve at its free end, said valve and apertured tubular part being adapted when extended relative 125
- 45 8. A vibratory feed lubricator comprising a basal portion having a cylindrical extension and an outlet therefrom, opposed sight apertures in said extension, a transparent tube seated in said extension, a funnel shaped nipple for clamping said transparent tube in position, a dished diaphragm mounted in spaced relation within the aforementioned basal portion, a lubricant reservoir having a cylindric body portion, a base having an in-

to the perforate tube to close communication between the reservoir and dished diaphragm and open said reservoir for filling purposes.

8. In a vibratory feed lubricator the combination of a basal portion having an outlet therefrom, a funnel shaped nipple seated over said outlet, a dished diaphragm mounted in spaced relation within said basal portion, a lubricant reservoir mounted on and adapted for clamping engagement to said basal portion, a perforate tube axially longitudinal of the reservoir and having threaded connection in the lower end thereof, the

perforations in said tube creating a trap for preventing solid matter passing from said reservoir to the part to be lubricated, means for manipulating said perforate tube whereby its lower end may be regulated relative to the dished diaphragm, and an upwardly seating valve and connected telescopic member movable longitudinally within the perforate tube to open an aperture in said telescopic member whereby the lubricator may be filled when necessary.

In testimony whereof I affix my signature.

ALLEN A. VAN ORSDALE.
